UNITED STATES PATENT OFFICE.

MARTIN JOHNSON LOVE, OF ASHLAND, OREGON.

RADIO RECEIVING APPARATUS.

Application filed August 28, 1925. Serial No. 53,162.

This invention relates to radio receiving apparatus and has for its object the provision of a novel circuit by means of which static, strays and other interferences will be 5 filtered out or trapped and consequently eliminated so that reception will be greatly clarified and the signal strength increased.

An important object is to provide an apparatus and circuit which embodies filtering inductances together with variable capacitors all of which will coact, when properly adjusted, to accomplish the desired results.

Another object is to provide a circuit which will involve the use of only a comparatively 15 small number of instruments which may be easily connected and adjusted without requiring any excessive degree of skill so that the operation may be carried out by a person of ordinary intelligence.

With the above and other objects and advantages in view, the invention consists in the details of construction and arrangement of parts to be hereinafter more fully described and claimed, and illustrated in the accompanying drawings in which:

Figure 1 is a view of a radio set constructed in accordance with the invention, this view showing in elevation, the instruments mounted on the rear of the panel and also showing 30 in top plan, the instruments mounted on the base,

Figure 2 is a diagram of the circuit.

Initially, it might be mentioned that it is the peak values that should be the same on 35 any wave length in the reception of radio broadcasting.

As a consequence, the energy content of the static surge with the secondary will be less than that of the signals, a condition which 40 makes it possible to utilize filtering means for the removal or trapping out of these interfering conditions.

In carrying out the invention I preferably make use of the apparatus disclosed in the 45 drawings wherein the letter X designates a panel and B the base board. Mounted on the panel I have shown a variable condenser V⁴ of suitable capacity connected with the antenna terminal or binding post I⁹, this condenser being connected with one terminal of an inductance L⁵. The wave band is lowered to a low meter or low frequency through an inductance coil L¹¹ which is in close coupling with an inductance L¹⁰. In actual practice the 55 inductance L¹⁰ is preferably a coil of copper tubing which may conveniently have five

turns of a diameter, say, of three inches, in which coil is located the coil L¹¹ which passes through the entire length. It is at this point that the interference is trapped out. The coil L¹⁰ is connected to coil L⁸. At this point the circuit is split, a portion of the antenna current passing through the coil L⁵ and through the condenser V⁴, another portion of the current passing through the coils L² and L¹ and being grounded through the variable switch S¹ and also the switch S², enabling the operator to cut that part of the coil L¹ to obtain the proper values of inductance through a by-pass from switch S² to coil L². The other 60 side of the coil L¹⁰ is grounded to the binding post or terminal I⁵ in sets designed for use in connection with a loop antenna. This side of the coil L¹⁰ connects to the negative side of the pole of the magnet M to prevent the strays 65 from passing through the magnet.

The coil L⁴ is preferably shunted by a variable condenser V³ of suitable capacity. The positive side of this part of the inductance circuit is connected with the stator plates of the variable condenser V³, the rotary plates of which are connected to the inside of the coil L⁴ and onto the binding post I⁶ for the antenna. The negative side of the coil L⁴ is connected to the binding post I⁷ provided for 70 connection with a B battery. The rotary plates of the condenser V² are also connected to the positive side of the coil L⁷, the inside of which connects to the positive side of the magnetic coil L⁸. The inside of coil L⁸ connects to the radio frequency side of the crystal detector or rectifier C. The audio frequency terminal of the crystal connects to the inside of the magnetic coil L⁹ so that current 75 will pass through this coil to the binding post I² and to the coil L¹¹.

The positive side of this circuit is split between the coil L¹¹ and the coil L⁸, passing through a potentiometer P back to inside of the coil L⁶ and outside of coil L⁶ is connected 80 to the rotary plates of the variable condenser V¹. The stationary plates of this condenser are connected to the inside end of the coil L⁶. In other words, this variable condenser V¹ is shunted across the coil L⁶ and is used as a 85 filter for this part of the circuit. I also provide a rheostat R which is connected to the binding post I⁴ where the negative terminal of the B battery is connected, and this rheostat is used to vary the resistance of the 90 current through the condenser D³ to the coil L⁶ and to condenser V¹, the condenser D³ 95

being of the fixed type. The condenser D^1 , likewise of fixed type and of a higher capacity, is shunted across the potentiometer P and is used to smooth out the high frequencies in this part of the circuit. The fixed condenser D^2 is shunted across the coils L^9 and L^7 to build up the signal strength through the condensers V^2 and V^3 to coil L^4 and the connection I^7 .

10 From the foregoing description and a study of the drawings it will be apparent that I have thus provided a very simple radio circuit involving the use of a comparatively small number of instruments or auxiliary devices for greatly improving reception over what is ordinarily possible with the well known types of arrangements. Attention is directed to the fact that adequate means has been provided not only for tuning purposes 15 but also for trapping out and eliminating strays, static and in fact all undesired impulses. It is believed that the construction,

operation and advantages will be readily apparent to one skilled in the art without further explanation.

25

While I have shown and described a preferred embodiment of the invention, it should be understood that I reserve the right to make such changes in the form, construction and arrangement of parts as will not depart from the spirit of the invention or the scope of the subjoined claim.

30

Having thus described the invention, I claim:

35

In a radio receiver an input circuit including closely coupled tuned inductances, interference and static eliminating means comprising a horseshoe permanent magnet, inductances arranged between the pole pieces thereof and connected in series with said input circuit, and a crystal detector connected in series with the last named inductances.

40

In testimony whereof I affix my signature.

MARTIN JOHNSON LOVE.
